CONTROL DEVICE

Andrew K. Foulds, Grosse Pointe Park, Detroit,
Mich., assignor to Detroit Lubricator Company,
Detroit, Mich., a corporation of Michigan

Application January 3, 1933, Serial No. 649,940

10 Claims. (Cl. 137—68)

My invention relates to new and useful improvements in control devices, and more particularly to a device for maintaining a substantially constant liquid level.

- 5 An object of my invention is to provide a control device which is operable to maintain a substantially constant head of liquid for supply to a burner, for example, and in which a safety means is provided to insure closing of the constant level valve if the level of liquid increases above the predetermined desired level. This safety means comprises a float which is responsive to increase of liquid level above the predetermined level.
- 15 The invention consists in the improved construction and combination of parts, to be more fully described hereinafter and the novelty of which will be particularly pointed out and distinctly claimed.
- 20 In the accompanying drawing, to be taken as a part of this specification, I have fully and clearly illustrated a preferred embodiment of my invention, in which drawing—

Figure 1 is a view in section on the line 1—1 of Fig. 2 of the control device embodying my invention; and

Fig. 2 is a view in section on the line 2—2 of Figure 1.

Referring to the drawing by characters of reference, 1 designates, generally, a casing containing a chamber or reservoir 2 and having a bottom wall 3 from which rises a continuous surrounding wall 4. Through the bottom wall 3 there is an aperture 5 in which is positioned an inlet member 6 which projects into the chamber 2 and also extends below the bottom wall 3. This member 6 is provided with an upwardly facing shoulder 7 which engages the under face of the bottom wall 3 and which is clamped thereto by a nut, or the like, 8 positioned within the chamber 2 and screw-threaded onto the member 6. The member 6 has a passage 9 therethrough which comprises the inlet to the chamber 2 and which is enlarged as at 10 to provide a valve chamber, and which also provides an upward facing shoulder 10^a defining a valve seat. Screw-threaded, or otherwise secured, within the chamber 10 is a sleeve member 11 having a lateral flange 12 at its upper end which overlies the upper end of the member 6. Supported on the member 6 is a supporting means or bracket 13 having a base portion 14 which is apertured to receive the sleeve member 11 and which is clamped between the flange 12 and the member 6. The inlet end 15 of the passage 9 is provided with a strainer 16

and an externally threaded nipple 16 by which the control device may be connected to a source of liquid supply. Within the chamber 10 there is a valve member 17 guided for reciprocation in a spider, or the like, 18 rigidly supported by 5 the sleeve member 11. The valve member 17 is provided at its opposite ends with valve faces 19 and 20. The valve face 20 cooperates with the shoulder 10^a to control the passage 9 and the valve face 19 cooperates with a downward 10 facing shoulder 21 which provides a valve seat formed by a reduction in the diameter of the bore through the sleeve member 11. The valve member 17 has a stem 22 which extends upwardly through the bore in the sleeve member 11 and 15 preferably terminates above the top of the chamber 2. Rigidly secured on the stem 22 is a collar, or the like, 23 having opposed vertically spaced flanges 24 and 25 which receive one end 26 of an operating arm or lever 27 which is pivotally supported or fulcrumed on a shaft 28 supported at its ends in the arms of the supporting means 13. The other end 29 of the lever 27 carries a float 30 which is preferably rigidly secured thereto. The flange 25 is preferably longitudinally movable on the member 23 and is held in engagement with the lever 26 by a coil spring 31 which is held under compression between the flange 25 and a shoulder 32 on the member 23. The flange 32 is preferably carried by a nut screw-threaded 30 onto the end of member 23. The float 30 on downward movement acts through the lever 27 and flange 24 to raise the valve face 20 from its seat 10^a but the extent to which the valve face 20 may be lifted by the float 30 is limited by a stop 35 member 30^a preferably rigid with one of the arms of the supporting member 13. This member 30^a projects beneath the lever 27 and serves to limit the downward movement of the lever end 29 by the float 30 but due to the spring 31 the stem 22 40 may have further upward movement sufficient to engage the valve face 19 with its seat 21 to close the inlet 9.

The reservoir 2 is provided with a cover or closure member 33 preferably seating on and 45 secured to a lateral surrounding flange 34 formed at the top edge of the wall 4. The cover member 33 has an extension 35 which projects beyond the flange 34 and which has downwardly directed, substantially parallel, supporting arms 36. Supported by the arms 36 is a hollow casing or container 37 which comprises an overflow chamber. The container 37 has oppositely positioned supporting arms 38 which extend upwardly into co-operable relation with the arms 36 and which are 50 55

pivottally secured thereto by pins, or the like, 39. The wall 4 has an aperture 40 in which is secured an overflow spout, or the like, 41 which projects through a slot 42 in the side wall of the 5 container 37, the slot being open at its upper end so that the container may be swung outward for emptying. Above the member 41 the side wall 4 is provided with a substantially vertical opening 43 through which a lever member 44 projects. The lever member 44 has reinforcing, depending, side flanges 45 and has laterally extending, oppositely directed arms or trunnions 46. The side wall 4 has oppositely positioned apertures 47 which receive the ends of the arms 46 10 and in which the lever is supported for rocking movement. The end of the lever within the chamber 2 is tapered as at 48 and receives a spring cup 49 against which one end of a helical coil spring 50 seats. The other end of the spring 20 50 seats against a cup member 51 which bears against an adjustable abutment member 52 rigid with the wall 4. This member 52 is preferably in the form of an adjustable screw having a conical end 53 and screw-threaded in a sleeve member 25 54 rigidly fixed in the wall 4. The spring 50 is under compression so that its force, which may be regulated by the screw 52, normally acts to hold the lever 44 in the position shown in which the flanges 45 are in engagement with the bottom 30 edge of the opening 43 which serves as a stop to limit movement of the lever 44. The stem 22 extends through a longitudinal slot 55 in the lever 44 and has rigidly secured thereto above the lever 44 an abutment member 56. The other 35 end 57 of the lever 44 which extends through the opening 43 and outside of the casing 1 terminates substantially midway between the supporting arms 38 of the container 37. Secured between the flanges 45 by a pin 58 is a depending hollow 40 push rod 59 which is provided at its lower end with a surrounding flange 60. Secured at substantially the midpoint of the bottom wall of the container 37 there is a guide rod 61 which extends upwardly into the bore of the rod 59. Positioned within the container 37 beneath the 45 flange 60 there is a float 62 having a central vertical bore 63 therethrough which receives the rod 61 for retaining and guiding the float 62. The cover member 33 is provided with an aperture 50 in line with the stem 22 and in which is fixed a guide sleeve 64 which surrounds the upper end of the stem 22, the stem 22 projecting thereabove, as at 65, so that it may be manually operated. The casing 1 is provided with a supporting bracket 66 having an aperture 67 therethrough to receive the member 6. The bracket 66 is rigidly clamped to the casing 1 by a nut 68 screw-threaded onto the member 6. The reservoir 2 is provided with an outlet 69 which opens 55 through the bottom wall 3 and which is preferably controlled by a manually adjustable valve having a stem 70. The operation of my control device is as follows: When the inlet 8 has been connected at the 65 nipple 16 to a source of supply and the outlet 69 has been connected to a point of discharge such as a burner, for example, liquid will enter the chamber 2 through the open passage 9 since the valve faces 20 and 19 are each out of engagement 70 with their respective seats. As the level of liquid rises in the chamber 2, the float 30 will be lifted and acting through the lever 27 upon the collar flange 25 will move the valve face 20 toward inlet closing position. When the predetermined desired level has been reached in the chamber 2, 75 the float 30 will seat the valve 17 against its seat 10^a and close the passage 9. This lever will be maintained substantially constant by the float 30 which serves on any decrease in the lever to open the valve 17 with respect to its seat 10^a. If the valve face 20 fails to seal the passage 9 so that the level in the chamber 2 continues to increase, then when the level in the chamber reaches the height of the overflow spout 41 liquid will discharge from the chamber 2 into the container 37. As the liquid level rises in the container 37, the float 62 will rise with it and acting against the flange 60 will move the rod 59 upward. Upward movement of the rod 59 will carry with it the end 51 of the lever 44, turning the lever 44 about its fulcrum on the arms 46. When the lever 44 has moved upward sufficient to carry the point of engagement between the lever and the spring 50 overcenter, the force of the spring will act to quickly move the lever 44 upward against the abutment member 56. The quickly moving lever 44 will sharply impact the valve stem through the medium of the abutment member 56 and will carry the stem 22 and its valve member 17 upward to seat the valve face 19 against seat 20 21 with a driving force, thereby tightly to close the passage 9. Upward movement of the stem 22 is permitted by the longitudinally movable flange 25 even though the lever 27 be in engagement with the stop 30^a or the resistance of the float 30 30 to immersion be sufficient to resist movement of the lever 27 by the spring 50. After the valve has been closed by operation of the float 62, the container 37 may be emptied by swinging the container 37 outward or away from the casing 1 35 on its supporting members 39 to pour the liquid therefrom. When the cause of failure of the float 30 to function has been remedied, the device can be placed again in normal operation by returning the container to vertical position and by manually moving the lever 44 into the position shown in Figure 2.

What I claim and desire to secure by Letters Patent of the United States is:

1. A device of the character described, comprising a casing having a reservoir with an inlet and an outlet, means controlling said inlet, said means having a stem, a float having a lost-motion connection with said stem and operable to maintain a substantially constant liquid level in said reservoir, a lever cooperable with said stem to close said inlet, overcenter means acting on said lever, said last-named means exerting its force in one position to maintain said lever inactive and exerting its force of movement overcenter to urge said lever into cooperable engagement with said stem whereby to close said inlet, stop means engageable by said lever upon its movement to inactive position to limit movement of said lever, and a float responsive to a predetermined increase of liquid level above said constant level and operable to move said overcenter means overcenter, said lost-motion connection permitting movement of said stem relative to said first-named float upon engagement of said lever with said stem. 45 50 55 60 65 70 75
2. A device of the character described, comprising a casing having a reservoir with an inlet and an outlet, means controlling said inlet, said means having a stem, a float operatively connected to said stem and operable to maintain a substantially constant liquid level in said reservoir, a lever engageable with said stem to move said means to close said inlet, a spring disposed within said reservoir and having one end fixed to said 70 75

- casing and having its other end engaging said lever, the point of engagement between said spring and said lever being movable overcenter, said lever having an end portion projecting exteriorly of the casing, said spring normally acting to maintain said lever inactive, said spring acting on movement overcenter to close said inlet, and a float responsive to a predetermined increase of liquid level above said constant level and cooperable with said lever, said second-named float acting on movement to move the point of engagement between said spring and said lever overcenter whereby said spring will act to close said inlet, said projecting portion of said lever serving as a manually operable means for positioning said spring in its inactive position and for positioning said spring in its active position.
3. A device of the character described, comprising a casing having a reservoir with an inlet and an outlet, means controlling said inlet, supporting means in said reservoir, a lever having operative engagement with said controlling means and fulcrumed on said supporting means, a float positioned in said reservoir and carried by said lever, said float acting to maintain a substantially constant liquid level in said reservoir, a lever member fulcrumed intermediate its ends in said casing, an adjustable abutment member projecting from a side wall of said casing and positioned in opposed relation to one end of said lever member, a helical coil spring positioned between said abutment member and said lever member end and held under compression therebetween, the point of engagement between said spring and said lever member being movable overcenter, said lever member being movable into cooperative engagement with said controlling means, and a second float responsive to a predetermined increase of liquid level above said constant level and cooperable with said member, said second float acting on movement to move said spring overcenter whereby to move said controlling means to close said inlet.
4. In a liquid level control device, a casing having a chamber for liquid and an inlet port therefor, a valve controlling said port and having a stem portion, a float in said chamber operable in response to changes in liquid level therein to actuate said valve to maintain a substantially constant liquid level in said chamber, a lever fulcrumed within said casing and having one end connected to said float, and a coil spring surrounding said valve stem and carried thereby with one end acting on said valve stem and the other end acting on the other end of said lever.
5. In a liquid level control device, a casing having a chamber for liquid and an inlet port therefor, a valve member controlling said port and having a stem portion extending vertically upward therefrom, said valve stem portion having a flange member integral therewith, a float in said chamber operable in response to changes in liquid level therein to operate said valve member to maintain a substantially constant liquid level in said chamber, a lever fulcrumed within said chamber and having one end connected to said float, a flange member surrounding said stem portion and movable longitudinally relative thereto, the other end of said lever being disposed between said flange members for bearing thereagainst to actuate said valve member, spring means urging said movable flange member toward said first-named flange member, and float operated means operable in response to an increase in liquid level to a predetermined level for moving said valve member to closed position.
6. In a liquid level control device having a chamber for liquid and an inlet passage therefor, a valve member controlling said passage and having an upwardly extending stem portion, said stem portion having a lateral flange member, a float in said chamber actuating said valve member to maintain the liquid level substantially constant, a lever fulcrumed within said casing with one end connected to said float and the other end disposed for engagement with the underside of said flange member, a coil spring surrounding said valve member with one end fixed relative thereto and the other end urging said last-named lever end toward said flange member, said spring serving to operatively connect said float and said valve member without lost motion therebetween when the level of the liquid is maintained substantially constant, abutment means on said stem portion and a safety cut-off means including a normally inactive lever member disposed in spaced relation to said abutment means and operable upon a predetermined increase in liquid level above the substantially constant level for engaging said abutment means and moving said valve member to close said passage, a float for actuating said safety cut-off means, said spring permitting relative movement between the valve member and said first-named float when said valve member is actuated by said lever member.
7. A liquid level control device comprising a casing having a reservoir for liquid, float operated valve means effective to maintain a substantially constant liquid level in said reservoir, safety cut-off mechanism operable to stop admission of liquid to said reservoir upon rise of liquid level in said reservoir to a predetermined level above said constant level, lever mechanism having a part within said reservoir and operable upon movement to move said valve means to stop admission of liquid to said reservoir, means within said reservoir operable to hold said lever mechanism in inactive position, liquid level responsive means operable upon occurrence of said predetermined liquid level to move said holding means to release said lever mechanism so that said lever mechanism will act to move said valve means, said lever mechanism having means projecting exteriorly of said casing, said projecting means being operable upon movement in one direction to position said lever mechanism in its said inactive position and being also operable upon movement in another direction to move said holding means thereby to release said lever mechanism so that said lever mechanism will move and hold said valve means in position to stop admission of liquid to said reservoir.
8. A device of the character described, comprising a casing containing a constant level chamber having an inlet and an outlet, means having a stem and controlling said inlet, said stem having a bearing surface, an overflow chamber adjacent said constant level chamber, said casing having a wall separating said chambers, said wall having an overflow passageway establishing communication between said chambers, a removable cover member secured on said casing and overlying said chambers, a normally inactive lever pivotally supported within said casing and positioned for movement into engagement with said stem bearing surface to move said stem thereby to close said inlet, a float member in said overflow chamber, means holding

- said lever in spaced relation to said bearing surface and in inactive position, said holding means having operative connection with said float member and releasable by said float member upon overflow into said overflow chamber, a float member in said constant level chamber, a second lever pivotally supported in said casing and carrying said second-named float member, and a lateral projection on said stem and cooperable with said second-named lever whereby said second-named float member can actuate said controlling means, said stem being movable relative to said second-named lever upon operation of said controlling means by said first-named lever.
9. A device of the character described, comprising a casing containing a constant level chamber having an inlet and an outlet, controlling means having a stem and controlling said inlet, said stem having a bearing surface, an overflow chamber adjacent said constant level chamber, said casing having a wall separating said chambers, said wall having an overflow passageway establishing communication between said chambers, a removable cover member secured on said casing and overlying said chambers, normally inactive lever means pivotally supported within said casing and having a part positioned adjacent said bearing surface for movement into engagement with said stem bearing surface to move said stem thereby to close said inlet, a float member in said overflow chamber, a spring having one end fixed, said spring acting on said lever means and operable to urge said controlling means to closed position upon movement of said lever means, said float member hav-
- ing operative connection with said lever means so that said lever means will be moved upon overflow into said overflow chamber, a float member in said constant level chamber, a second lever pivotally supported in said casing and carrying said second-named float member, and a lateral projection on said stem and cooperable with said second-named lever whereby said second-named float member can actuate said controlling means, said stem being movable relative to said second-named lever upon operation of said controlling means by said lever means.
10. In a liquid level control device having a reservoir in which liquid is normally maintained at a substantially constant liquid level controlled by a float operated valve, a safety cut-off mechanism for stopping entrance of liquid to said reservoir when the level of the liquid therein rises to a predetermined level comprising, a lever fulcrumed within said reservoir and having an arm operable upon movement to actuate said valve to stop flow of liquid, said lever having an active and an inactive position, means within said reservoir normally holding said lever in its inactive position, a float operable for moving said holding means to release said lever for such movement of its said arm upon increase in liquid to a predetermined level above said substantially constant level, said lever having an end portion extending exteriorly of the reservoir and serving as a manually operable means for positioning the lever in its inactive position and for also positioning said lever in its active position holding said valve in closed position.

CERTIFICATE OF CORRECTION.

Patent No. 2,139,616.

December 6, 1938.

ANDREW K. FOULDS.

It is hereby certified that error appears in the printed specification of the above numbered patent requiring correction as follows: Page 2, second column, lines 2 and 4, for the word "lever" read level; line 55, claim 1, for "of" read on; page 3, first column, line 41, claim 3, before the word "member" insert lever; and second column, line 21, claim 6, after "portion" insert a comma; and that the said Letters Patent should be read with this correction therein that the same may conform to the record of the case in the Patent Office.

Signed and sealed this 7th day of February, A. D. 1939.

Henry Van Arsdale.

Acting Commissioner of Patents.

- said lever in spaced relation to said bearing surface and in inactive position, said holding means having operative connection with said float member and releasable by said float member upon overflow into said overflow chamber, a float member in said constant level chamber, a second lever pivotally supported in said casing and carrying said second-named float member, and a lateral projection on said stem and cooperable with said second-named lever whereby said second-named float member can actuate said controlling means, said stem being movable relative to said second-named lever upon operation of said controlling means by said first-named lever.
9. A device of the character described, comprising a casing containing a constant level chamber having an inlet and an outlet, controlling means having a stem and controlling said inlet, said stem having a bearing surface, an overflow chamber adjacent said constant level chamber, said casing having a wall separating said chambers, said wall having an overflow passageway establishing communication between said chambers, a removable cover member secured on said casing and overlying said chambers, normally inactive lever means pivotally supported within said casing and having a part positioned adjacent said bearing surface for movement into engagement with said stem bearing surface to move said stem thereby to close said inlet, a float member in said overflow chamber, a spring having one end fixed, said spring acting on said lever means and operable to urge said controlling means to closed position upon movement of said lever means, said float member hav-
- ing operative connection with said lever means so that said lever means will be moved upon overflow into said overflow chamber, a float member in said constant level chamber, a second lever pivotally supported in said casing and carrying said second-named float member, and a lateral projection on said stem and cooperable with said second-named lever whereby said second-named float member can actuate said controlling means, said stem being movable relative to said second-named lever upon operation of said controlling means by said lever means.
10. In a liquid level control device having a reservoir in which liquid is normally maintained at a substantially constant liquid level controlled by a float operated valve, a safety cut-off mechanism for stopping entrance of liquid to said reservoir when the level of the liquid therein rises to a predetermined level comprising, a lever fulcrumed within said reservoir and having an arm operable upon movement to actuate said valve to stop flow of liquid, said lever having an active and an inactive position, means within said reservoir normally holding said lever in its inactive position, a float operable for moving said holding means to release said lever for such movement of its said arm upon increase in liquid to a predetermined level above said substantially constant level, said lever having an end portion extending exteriorly of the reservoir and serving as a manually operable means for positioning the lever in its inactive position and for also positioning said lever in its active position holding said valve in closed position.
